MOLDING FLASK CLAMP

Ernest Huff, Elm Grove, Wis., assignor to Wehr Steel Company, West Allis, Wis., a corporation of Wisconsin

Application August 28, 1942, Serial No. 456,472

3 Claims.

(Cl. 22—109)

This invention relates generally to improvements in the art of molding, and relates more specifically to improvements in the construction and operation of rigs for clamping molding flasks or the like to supports such as the pattern supporting plates of roll over molding machines.

An object of the present invention is to provide a new and useful molding flask clamp which is simple in construction and highly efficient in operation.

Many different types of clamping assemblages for detachably attaching molding flasks to the pattern supporting plates of roll over molding machines such as are employed in foundries, have heretofore been proposed and used with varying degrees of success. In order to function effectively, this kind of equipment must be quickly operable to firmly clamp and to release flasks of various sizes and shapes, so as to avoid loss of time, and the clamping rig should also be constructed and disposed so as to prevent interfering with the molding operations. While fluid pressure operated clamps have been used in the past, these prior devices were relatively complicated and positioned at the sides or ends of the pattern supports where they were not only obstructive, but could not be universally applied to different parts of the opposite portions of flasks of various depths, and the utility of such prior power clamps was therefore relatively limited. In order to enhance the usefulness of these flask clamping and releasing assemblies to a maximum, they should be extremely powerful in action, compact and durable in structure and confined to non-interfering localities, readily applicable to various types of pattern supports, protected against injury but open to ready inspection, and cooperable with the opposite side portions of deep or shallow flasks throughout a considerable range of lateral adjustment.

It is therefore a more specific object of my present invention to provide an improved fluid pressure actuated molding flask clamp which meets all of the above mentioned requirements, and which is extremely flexible in its adaptations and uses.

Another specific object of the present invention is to provide an improved molding flask clamping system which can be readily applied to either new or old molding machines of various standard types at moderate cost, and which may be safely and conveniently manipulated to meet varying conditions of operation and use.

These and other specific objects and advan-

tages of the present improvement will be apparent from the following description.

A clear conception of one embodiment of the present invention, and of the construction and operation of a molding flask clamping rig built in accordance with the improvement, may be had by referring to the drawing accompanying and forming a part of this specification wherein like reference characters designate the same or similar parts in the various views.

Fig. 1 is a somewhat diagrammatic part sectional side elevation of a conventional roll over pattern support and inverting bracket, showing a mold disposed thereon and having the improved flask clamping system applied thereto;

Fig. 2 is a bottom view of the assemblage of Fig. 1, showing the disposition of the improved flask clamping system, and with the fluid distribution and control apparatus shown diagrammatically; and

Fig. 3 is a transverse vertical section through a fragment of one side of the assemblage shown in Figs. 1 and 2.

While the invention has been illustrated herein as being specifically embodied in an air pressure actuated clamping assemblage applied to a particular type of roll over molding machine, it is not my desire or intent to unnecessarily restrict the scope or utility of the improvement by virtue of such specific embodiment. Molding machines of the roll over class, are ordinarily constructed to permit packing of the sand about the pattern either by high velocity injection thereof into the upper open end of the flask, or by loose deposition of the sand within the flask and subsequent jolting; and my present invention is applicable to both of these types of machines.

Referring to the drawing, the conventional roll over molding machine specifically illustrated therein is of the high velocity sand injection type, and comprises a pattern support or supporting plate 5 fixedly mounted upon the swinging end of an inverting bracket 6 which is suspended from a pivot 7, and having a series of parallel recesses 8 therein for effecting rigid attachment of a pattern 9 thereto with the aid of bolts 10 or the like. The successive molding flasks 11 within which the molds 12 are formed, are adapted to be positioned upon the supporting plate 5 about the pattern 9 while the mechanism is in the position shown in Fig. 1, and with the parts thus positioned the sand may be packed about the pattern in any well known manner. Upon completion of each mold 12, the supporting plate 5 with the flask 11 and mold 12 firmly secured thereto must

normally be inverted, whereupon the flask should be released for final withdrawal of the pattern 9 from the mold 12. After the draw, the plate 5 and bracket 6 should be returned to molding position for the reception of another flask 11, and the shape and depth of these flasks 11 varies throughout a considerable range depending upon the size and shape of the patterns 9 which are being used. Since the flasks 11 and molds 12 are relatively large and heavy, these mold assemblages must be rigidly but releasably attached to the pattern support in order to prevent possible shifting or distortion of the molds during inversion, and this invention deals primarily with the construction and operation of an improved rig for effecting such attachment and release of the flask and mold relative to the pattern support.

The present improved clamping and releasing system or rig, comprises in general a pair of fluid pressure actuated motors 14 each having a cylinder 15 fixedly suspended beneath the pattern supporting plate 5, and a piston 16 reciprocable within its cylinder 15 and provided with a piston rod 17; a pair of flexible elongated elements or cables 18 each having one end swingably attached to one of the piston rods 17, while its medial portion is adapted to coat with a rotary guiding member or sheave 19 also suspended beneath and near an edge of the supporting plate 5; a clamping device or hook 20 swingably connected to the opposite freely swinging end of each cable 18, these devices being cooperable with the opposite sides of a flask 11 resting upon the plate 5; and means for simultaneously operating the motors 14 to pull on the cables 18 and to release the pulls or tension thereon, including a control valve 21 and fluid distribution piping 22, 23.

The motors 14 while being simultaneously operable, are reversely disposed, and the cylinders 15 of these motors are arranged approximately parallel to each other and may be fixedly suspended either from the bracket 6 or directly from the bottom of the pattern supporting plate 5 at any convenient location, by means of brackets 25 or otherwise. The motors 14 may be operated by compressed air or other suitable fluid under pressure derived from any suitable source, and the strokes of the pistons 16 and rods 17 should be sufficient to permit movement of the hooks 20 throughout a considerable range. The opposite ends of the elongated flexible elements or cables 18 may be swingably and durably connected to the rods 17 and hooks 20 by means of loop connectors 26, and the guide sheaves 19 are freely rotatable in brackets 27 which may also be suspended either from the bracket 6 or directly from the plate 5, near the opposite edges of the latter as shown. The clamping hooks 20 are of conventional design, and may be replaced by any other type of clamping device, and due to the flexibility of their carrying cables 18, these clamps are freely universally movable and adjustable throughout extended areas above the pattern support. When the hooks 20 are in action as shown in Figs. 1 and 3, they preferably coat with opposite side portions of the flask 11 as indicated in Fig. 2, and firmly retain the flask 11 in predetermined position upon the plate 5; but when the tension on the cables 18 is released and the clamping devices are removed from the work, the hooks 20 may be dropped below the pattern support, thus avoiding all fixed obstructions disposed above the upper pattern supporting surface of the plate 5.

The control valve 21 for effecting manual control of the fluid pressure actuated clamping system, may be located at a conveniently accessible place near the roll over machine controls, and 5 is adapted to simultaneously admit fluid such as air under pressure from a supply line 28 to either set of corresponding piston displacement chambers of the motors 14, while at the same time releasing the pressure from the opposed displacement chambers of these motors through an exhaust line 29. If clamping action is desired, the valve 21 should be set as illustrated in Fig. 2, thereby admitting fluid pressure to the adjacent or front displacement chambers through the piping 23, while at the same time permitting escape of fluid from the rear displacement chambers through the piping 22. If release of the 10 clamps is desired, the valve 21 should be set to admit fluid pressure to the rear displacement chambers through the piping 22, while at the same time permitting escape of fluid from the front displacement chambers through the piping 23. This control system is shown diagrammatically for the sake of clearness, and should 15 preferably permit independent initial adjustment or positioning of the pistons 16 and rods 17.

The normal use and operation of the improved mold flask clamping ring should be clearly apparent from the foregoing detailed description of its 20 construction, from which it should also be apparent that my present invention provides an improved clamping assemblage which is simple, compact and durable in construction, and which is also powerful and highly efficient in operation. 25 The fluid pressure actuated servo-motors 15 may obviously be readily disposed in any convenient locality beneath the pattern supporting plate 5, thereby avoiding obstructions above this plate, and the flexible cables 18 and swing connectors 30 26 permit ready application of the clamping hooks 20 to either deep or shallow flasks 11 of different sizes and shapes, at the localities where the clamps will act most effectively. The improved 35 clamping assembly while being well protected against possible damage during normal use of the molding machine, is also readily accessible for inspection and manipulation, and the improved device is obviously highly flexible in its adaptations and uses. The guide sheaves 19 effectively 40 protect the flexible cables 18 against abrupt bending and possible resultant damage, and also facilitate lateral adjustment of the clamping hooks 20 in all directions above the pattern table. The use 45 of compressible fluid for actuating the motors 14 is not essential but highly desirable since it permits simplification of these motors and also permits automatic equalization of the tension in the cables 18 and distribution of the stresses on the 50 clamping rig. The improved power clamping system can be manufactured and applied to various 55 types of molding machines at moderate cost, may be quickly and safely operated to either clamp or release the successive flasks 11, and has proven 60 highly satisfactory and efficient in actual use.

It should be understood that it is not desired 65 to limit this invention to the exact details of construction, or to the precise mode of operation of the molding flask clamp, herein shown and described, for various modifications within the scope 70 of the appended claims may occur to persons skilled in the art.

I claim:

1. A molding flask clamp, comprising, a flask support, a fluid pressure actuated motor having a cylinder suspended from and beneath said support

and a piston movable within the cylinder, a peripherally grooved wheel journalled for rotation upon said support so that the axis of said piston is approximately tangent to one portion of the wheel groove and another portion of the latter is disposed slightly beyond an edge of the support, a flexible cable having one end secured to said piston and its opposite end universally movable above said support while its medial portion is cooperable with said wheel groove to provide a bending zone for the cable, and a clamping hook movably secured to said universally movable cable end.

2. A molding flask clamp, comprising, a flask support, several fluid pressure actuated motors each having a cylinder suspended from and beneath said support and a piston movable within its cylinder, several peripherally grooved wheels journalled for rotation upon said support, each of said wheels cooperating with one of said motors so that the axis of the motor piston is approximately tangent to one portion of the wheel groove and another portion of the latter is disposed slightly beyond the adjacent edge of the support, a flexible cable cooperating with each motor and wheel set and having one end secured to the corresponding piston and its opposite end universally movable above said support while its

medial portion is cooperable with the corresponding wheel groove to provide a bending zone for the cable, and a clamping hook movably secured to the universally movable end of each cable.

5. 3. A molding flask clamp, comprising, a flask support, several fluid pressure actuated motors each having a cylinder suspended from and beneath said support and a piston movable within its cylinder, several peripherally grooved wheels journalled for rotation upon said support, each of said wheels cooperating with one of said motors so that the axis of the motor piston is approximately tangent to one portion of the wheel groove and another portion of the latter is disposed slightly beyond the adjacent edge of the support, a flexible cable cooperating with each motor and wheel set and having one end secured to the corresponding piston and its opposite end universally movable above said support while its medial portion is cooperable with the corresponding wheel groove to provide a bending zone for the cable, a clamping hook movably secured to the universally movable end of each cable, and means for effecting simultaneous operation of all of said motors to effect simultaneous actuation of all of said clamping hooks.
